UNITED STATES PATENT OFFICE.

CHARLES LAW, OF PITTSTON, PENNSYLVANIA.

CHUTE.

SPECIFICATION forming part of Letters Patent No. 691,279, dated January 14, 1902.

Application filed April 29, 1901. Serial No. 57,943. (No model.)

To all whom it may concern:

Be it known that I, CHARLES LAW, a citizen of the United States of America, residing at Pittston, in the county of Luzerne and 5 State of Pennsylvania, have invented certain new and useful Improvements in Chutes, of which the following is a specification.

My invention relates to chutes, and more particularly to that class adapted to be used 10 in filling cars.

The principal objects of my invention are, first, to provide an efficient, durable, and convenient device adapted to meet the requirements and perform the functions of a first-class conveyer or chute; second, to so construct and arrange the same that it may be adjusted in such a manner as to fill the car evenly, and, third, to provide a chute constructed of manganese bronze, enameled iron, 15 or any other material upon which sulfur alkalies, vapors, fumes, &c., common to all coal 20 will have no effect.

The invention consists, in brief, in certain component and coöperative parts and the 25 novel manner of combination and arrangement of said parts, all of which will be hereinafter more fully described, and specifically pointed out in the appended claims, which are intended to accord in their terms, spirit, 30 and meaning with the prior state of the art and the existing law.

Before proceeding further with a detailed description of the several novel features of my invention I desire to distinctly state and 35 emphasize the fact that although I have shown in the accompanying drawings and described in the following specific description certain component and coöperative parts which I deem sufficiently improved and operative to 40 carry out the principles herein incorporated I do not confine myself to the exact details of construction so illustrated and described, since obvious departures may be made without deviation from the inherent and generic 45 features constituting the gist hereof.

In the drawings forming a part of this specification, Figure 1 is a top plan view. Fig. 2 is a side elevation.

Referring by letters to the drawings, A repre- 50 sents the breeches or braces, in which is de-

tachably secured the chute proper, consisting of two corresponding semicircular sections B, curved or flaring in opposite directions, with the edges of their respective walls tapering, as plainly shown at C, and terminating in a shallow concave portion D, the ends of which are provided with guides E, adapted to receive the adjustable sliding sections F, which are also provided with guides G, adapted to engage the edges of the portions D, and stays or braces H upon their free ends adapted to strengthen the sections and prevent the ends from becoming bent.

While I have neither shown nor described any device for suspending the chute over or 65 in a car, it is obvious that any well-known means may be employed without affecting the principle or operation thereof.

Having thus described the various features of my invention, what I claim as new, and desire to secure by Letters Patent, is—

1. In a chute, a breech, two corresponding semicircular sections detachably secured in the said breech, the said sections flaring in opposite directions, with their walls tapering 75 to shallow concaved surfaces, and adjustable concave sections attached to the free ends of the respective semicircular sections, substantially as shown and described.

2. In a chute, a breech having two corresponding semicircular sections detachably secured therein, the said sections flaring in opposite directions with the edges of their respective walls tapering to a shallow concave surface, guides upon the said concave surface, adjustable sliding sections upon the said guides and braces upon the said sliding sections, substantially as shown and described.

3. In a chute, the combination of a breech, detachable concaved sections of manganese 90 bronze or the like supported by said breech, the said sections flaring in opposite directions, and of similar sections adjustably connected to the free ends of the first-mentioned sections, substantially as shown and for the purpose set forth.

CHARLES LAW.
